LIGHTING FIXTURE LENS

Carl X. Meyer, St. Louis County, Mo., assignor to Day-Brite Lighting, Inc., St. Louis, Mo., a corporation of Missouri

Application March 17, 1958, Serial No. 50,044

Term of patent 14 years

(Cl. D48—16)

FIG.1

FIG.2

FIG.3

FIG.4

Fig. 1 is a perspective view of a lighting fixture lens as viewed from underneath showing my new design;

Fig. 2 is a plan view from underneath of the lens of Fig. 1;

Fig. 3 is a diagonal sectional view of the lens on the line 3—3 of Fig. 2 on a slightly reduced scale; and

Fig. 4 is a transverse sectional view of the lens on the line 4—4 of Fig. 2 on a slightly reduced scale.

The characteristic feature of my design for the lighting fixture lens disclosed resides in the tapered ribs which divide the stepped parallel prisms on the concave surface into triangular sectors as shown.

I claim:

The ornamental design for a lighting fixture lens, substantially as shown and described.
